Primary Examiner — Mitchell Siegel(74) *Attorney, Agent, or Firm* — McKee, Voorhees & Sease, P.L.C.(57) **CLAIM**

I claim the ornamental design for a golf ball mark repair tool, as shown and described.

DESCRIPTION

FIG. 1 is a top perspective view of the golf ball mark repair tool;

FIG. 2 is a bottom perspective view thereof;

FIG. 3 is a top plan view thereof;

FIG. 4 is a side view thereof; and,

FIG. 5 is a bottom plan view thereof.

The broken line showing is included for the purpose of illustrating and forms no part of the claimed design.

1 Claim, 2 Drawing Sheets
